UNITED STATES PATENT OFFICE.

ARNO A. EWALD, OF OAKFIELD, WISCONSIN.

TIRE-INFLATING DEVICE.

1,414,559.

Specification of Letters Patent. Patented May 2, 1922.

Original application filed October 21, 1920, Serial No. 418,497. Divided and this application filed September 22, 1921. Serial No. 502,414.

To all whom it may concern:

Be it known that I, ARNO A. EWALD, a citizen of the United States, residing at Oakfield, in the county of Fond du Lac and State of Wisconsin, have invented certain new and useful Improvements in Tire-Inflating Devices; and I do declare the following to be a full, clear, and exact description of the invention, such as will enable others skilled in the art to which it appertains to make and use the same.

This application relates to tire inflating devices and is divisional from my pending U. S. application, Serial No. 418,497. Inflation devices of the class involved herein are each provided with a vertically movable hose-carrying arm pivoted to a standard whose upper end carries a globe for displaying the words "Free air", advertisements, etc. Means are provided for raising the arm after each use of the hose and the aim of the present invention is to provide a novel association of parts obscured in the globe and standard for cushioning the return movement of the arm to prevent injury to any part.

With the foregoing in view, the invention resides in the novel construction and association of parts hereinafter described and claimed, the descriptive matter being supplemented by the accompanying drawings.

Figure 1 is a side elevation partly in section showing my invention.

Figure 2 is a horizontal sectional view as indicated by line 2—2 of Fig. 1.

In the drawings above briefly described, the numeral 1 designates a hollow standard adapted to rise from a garage floor, sidewalk or other appropriate support, as illustrated in the application above referred to. The upper end of the standard 1 is provided with a cap or head 2 which is swivelled thereon and carries a circular upstanding frame 3 for holding a pair of lenses 4, said frame and lenses forming a globe adapted to contain an electric light 5 whereby the device may be illuminated at night and advertising matter or the like displayed upon the lenses. The head 2 is provided below the frame 3 with an opening 6 and the inner end 7 of a tubular hose-carrying arm 8 extends through said opening and is pivotally

mounted on the head as shown at 9. The tire inflation hose 10 leads from a suitable source of pressure and extends upwardly through the standard 1 and the arm 8, the free end of said hose being adapted to depend from the upper end of the arm 8 (not shown) so that by pulling upon the hose, the arm will swing downwardly and permit easy application of the hose to the tires to be inflated. I have shown a vertical rod 11 in the standard 1 connected with the inner end 7 of the arm 8, the lower end of said rod being connected with a coiled spring or the like 12 which is secured in the standard 1 and serves to return the arm to raised position after it has been lowered for use.

To absorb the shock when the arm 8 is returned to a raised position, I rigidly mount a dash-pot cylinder 13 in the frame 3 as seen more clearly in Figure 1, the piston rod 14 of the dash-pot being connected in any preferred manner to the upper end of a rod 15 whose lower end is pivoted to the inner end 7 of the arm 8. The internal construction of the dash-pot is such as to permit the arm 8 to swing downwardly without any appreciable resistance, but when this arm is released and the spring 12 acts on the arm to return the same to vertical position, the piston 16 of the dash-pot is checked in its descent, with the result that the shock is absorbed and no injury occurs to any part.

While any suitable means may be employed for mounting the cylinder 13, I prefer to provide the lower end of said cylinder with a threaded stud 17 which is threaded in an opening 18 in the bottom of the frame 3, this portion of the bottom being in the form of a lug 19 extending into the opening 20 through which the rod 15 and the carrying conduit of the light 5 extends.

I prefer to employ a water-supply hose 21 leading from a water pipe 22 within the standard 1, so that the radiators of automobiles may be filled conveniently at the time of inflating the tires.

From the foregoing, it will be seen that I have provided a unique arrangement of parts for carrying out the object of the invention and since excellent results may be obtained from the details disclosed, they are preferably followed. It is to be understood, how-

ever, that within the scope of the invention as claimed, numerous minor changes may be made.

I claim:

- 5 1. A tire inflating device comprising a hollow standard, a head swivelled on the upper end of said standard and carrying a globe, one side of said head having an opening, a hose-carrying arm extending into the head
10 through said opening and pivoted to the head, means for normally raising said arm, and means confined in said globe and connected with the inner end of said arm, for cushioning the return movement of the latter to vertical position.
- 15 2. A tire inflating device comprising a standard, a head swivelled on the upper end of said standard and carrying a globe communicating with the interior of the standard, the side of said head having an opening, a hose-carrying arm pivotally mounted in said opening and extending into the interior of the head, counter-balancing means for said arm located in said standard and connected
20 to the inner end of said arm, a rod rising
25 to the inner end of said arm, a rod rising

from said inner end of the arm into said globe and a shock-absorbing device mounted in said globe and connected with the upper end of said rod.

3. A tire inflating device comprising a standard, a head swivelled on the upper end of said standard and carrying a globe communicating with the interior of the standard, the side of said head having an opening, a hose-carrying arm pivotally mounted in said opening and extending into the interior of the head, counter-balancing means for said arm located in said standard and connected to the inner end of said arm, a rod rising from said inner end of said arm into said globe, a dash-pot in said globe, the piston rod of said dash-pot being connected with the upper end of said rod, and a threaded stud on the cylinder of said dash-pot, the bottom of said globe having an opening into which said stud is threaded.

In testimony whereof I have hereunto set my hand.

ARNO A. EWALD.
